Primary Examiner—M. H. Tung[57] **CLAIM**

The ornamental design for an combined optical scanner and portable terminal, as shown and described.

DESCRIPTION

FIG. 1 is a top, rear, left-side perspective view of an combined optical scanner and portable terminal showing our new design;

FIG. 2 is a bottom plan view thereof;

FIG. 3 is a front elevational view thereof;

FIG. 4 is an left-side elevational view thereof;

FIG. 5 is a rear elevational view thereof;

FIG. 6 is a right-side elevational view thereof; and,

FIG. 7 is a top plan view thereof.
